UNITED STATES PATENT OFFICE.

EDWIN H. ARMSTRONG, OF YONKERS, NEW YORK, ASSIGNOR, BY MESNE ASSIGNMENTS, TO WESTINGHOUSE ELECTRIC & MANUFACTURING COMPANY, A CORPORATION OF PENNSYLVANIA.

WAVE SIGNALING SYSTEM.

Application filed June 8, 1922. Serial No. 566,684.

To all whom it may concern:

Be it known that I, EDWIN H. ARMSTRONG, residing at 1032 Warburton Avenue, Yonkers, in the county of Westchester, State of New York, have invented certain new and useful Improvements in Wave Signaling Systems; and I do hereby declare the following to be a full, clear, and exact description of the invention, such as will enable others skilled in the art to which it appertains to make and use the same.

This invention relates to an electric regenerative system for amplifying varying electric currents, particularly radio or other high frequency signaling currents, wherein the varying potential of the current to be amplified is impressed on the system and the relation between the amount of regeneration and the degree of damping of the system is periodically varied to produce transient free oscillations proportional to the amplitude of the impressed potential and wherein the resulting free oscillations and the system are continuously maintained in this transient ordinarily unstable state to obtain super-regenerative amplification or action as described in my Patent 1,424,065 granted July 25, 1922, on a co-pending application, Serial No. 480,563, filed June 27, 1921.

The invention has for its object the provision of a method and apparatus for improving the operation of vacuum valve super regenerative systems, particularly of the type in which the amount of regeneration, that is, the regenerative energy supplied to the system, (the so-called negative resistance) is varied, with respect to the degree of damping, that is, the rate of dissipation of the energy of the system.

I have discovered that the plate circuit of a vacuum valve in the signal wave frequency regenerative circuit of a super-regenerative system reacts inductively to the auxiliary frequency at which the periodical variation in the relation between the amount of regeneration and the degree of damping of the system takes place. This reaction unless neutralized considerably affects the response and generally lowers the stability of the system, resulting in the case of the reception and amplification of radio telephone signals, in poor quality of speech. To the end of overcoming this reaction and

in accordance with the invention, a tuning capacity, preferably a variable condenser, is connected in the wave frequency regenerative circuit in parallel with the vacuum valve. The condenser is adapted to be so adjusted as to compensate for and neutralize the undesirable inductive reaction. The proper adjustment may be readily obtained by listening to the response of the system, the maximum response thereof indicating the proper tuning point.

The form of circuit arrangement illustrated in the drawings is the preferred embodiment of the invention. It possesses marked advantages in readily enabling the insertion of the proper value of capacity in the circuit to compensate for and neutralize the inductive reaction produced within the system by the auxiliary frequency. A more complete understanding of the invention may be had by reference to the drawings and the accompanying description. In these drawings:

Fig. 1 illustrates diagrammatically a circuit arrangement adapted to operate in accordance with the invention; and Fig. 2 illustrates a more practical form of circuit arrangement in which a self oscillating vacuum valve is employed to supply the auxiliary frequency.

Referring now to Fig. 1, the source 1 of the incoming signaling or varying current to be amplified is associated with the tuned circuit 2, 3, containing the resistance 4, the circuit 2, 3 being connected in the grid circuit of the vacuum valve 5. The plate circuit of the valve 5 contains the feed-back coil 6 which is associated with the inductance 2 thereby serving to control the amount of regeneration in the wave frequency portion of the system.

The plate circuit of the valve 5, in accordance with the invention, is provided with a variable tuning condenser 7 by means of which the inductive reaction produced by the auxiliary frequency may be neutralized and compensated. In this case the auxiliary frequency is produced by means of the vacuum valve 8 connected in the plate circuit of the regenerative system which includes the valve 5. The alternator 9 or other source of electrical oscillations in combination with the valve 8 impresses a varying voltage on the plate circuit of the valve

5 thereby periodically varying the amount of regeneration of the system with respect to the degree of damping thereof.

6 The plate circuit of the valve 5 also includes the telephones 10, the bypass condenser 11, the inductance 12, and the condenser and inductance 13 and 14 respectively, by means of which the auxiliary frequency may be controlled. The choke 15 10 serves to bypass the direct current of the battery 16 about the condenser 13.

15 The mode of operation of this system is as follows: The alternating current or electrical oscillations produced by the source 9 are impressed on the valve 8 so as to produce in the plate circuit thereof a varying auxiliary frequency current which in turn is made effective in the plate circuit of the valve 5 wherein it serves to vary the 20 amount of regeneration of the system. If a continuous wave telephone signal arrives in the regenerative system, the wave or signal frequency currents will be amplified by super-regenerative action in groups 25 corresponding in frequency to the local auxiliary frequency current and in amplitude to the variations imposed by the speech. This complex wave is rectified by the valve 5 and transformed to two frequencies in the plate circuit of the valve, one a frequency corresponding to the local modulating frequency and the other corresponding to the received voice or speech frequency.

30 While the maximum regenerative tendency in the wave frequency regenerative system exists when the voltage of the plate of the valve 5 is a maximum, nevertheless on account of the lag in building up the 35 oscillations in the circuit 2, 3, 4, the maximum or peak values of the wave frequency current in this circuit lag behind the auxiliary frequency currents in the plate circuit of the valve 5. Hence, the rectified 40 currents of the auxiliary frequency in the plate circuit of the valve 5 lag behind the electromotive force impressed across it. Hence the valve of the system reacts inductively to the impressed electromotive 45 force of the auxiliary frequency. It is this inductive reaction which is avoided 50 and neutralized by the compensating tuning condenser 7.

55 In operation the system above described has an advantage of greatly increasing the response of the system, improving the stability of operation thereof, and the quality of the speech when radio telephone signals are received and amplified. The system 60 also permits ready suppression of harmonics which might be created by over-varying the potential of the plate circuit.

65 A more practical form of the invention is illustrated in Fig. 2. The wave frequency regenerative system of this arrange-

ment, is similar to that of Fig. 1, and like reference numerals have been employed for similar portions of the system. In this figure, as in the case of Fig. 1, the source 1 of the incoming signal is associated with the wave frequency regenerative amplifying system 2, 3, 4, 5, 6, 7 which is tuned to the wave frequency. In this arrangement, however, a self-oscillating valve system comprising a feed-back circuit including 70 the valve 17 is arranged to vary the plate voltage of the regenerative system. Otherwise the mode of operation of this system is identical with that described in connection with Fig. 1. 80

It is to be understood that the present invention is adapted to receive radio signals, including radio telephone signals, when associated with an antenna, loop or other energy collecting device and to receive wired wireless signals (so-called wire carrier current transmission) when associated with the conductor of such signals. It should also be understood that modifications may be made in the specific circuit 90 connections above described without departing from the spirit and scope of the invention.

I claim:

1. The method of operating a super-regenerative system having a certain degree of damping and which includes an oscillating system producing an auxiliary frequency for periodically varying the relation between the amount of regeneration 95 and the damping of the system, which includes producing an inductive reaction within the system, and neutralizing and compensating for said reaction.

2. An electric system adapted to produce super-regenerative action, including a wave frequency regenerative system having a certain degree of damping, means for periodically varying the relation between the amount of regeneration and the degree of 100 damping of the system, comprising an oscillating system adapted to supply an auxiliary frequency to the regenerative system whereby an inductive reaction is produced in said 110 system and means for neutralizing and compensating for said reaction.

3. An electric system adapted to produce super-regenerative action including a wave frequency vacuum valve regenerative system having a certain degree of damping, 120 means for periodically varying the relation between the amount of regeneration and the degree of damping of the system comprising a vacuum valve oscillating system adapted to supply the auxiliary frequency to the 125 regenerative system whereby an inductive reaction is produced in the regenerative system and a compensating capacity in said regenerative system adapted to neutralize 130 said reaction.

4. An electric regenerative system adapted to produce super-regenerative action, including a feed-back circuit having a certain degree of damping, a vacuum valve in said circuit, means for periodically varying the relation between the amount of feed-back and the degree of damping of the circuit comprising a self oscillating vacuum valve

system adapted to supply an auxiliary frequency to said circuit whereby an inductive reaction is produced therein and a compensating variable capacity connected in parallel with said valve in the feed-back circuit adapted to neutralize said reaction.

In testimony whereof I affix my signature.
EDWIN H. ARMSTRONG.
